UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW-REGULATOR DRUM.

Application filed November 5, 1923. Serial No. 672,792.

To all whom it may concern:

Be it known that ERNEST E. HEINTZ, a citizen of the United States, residing at Detroit, in the county of Wayne and State 5 of Michigan, has invented certain new and useful Improvements in Window-Regulator Drums, of which the following is a specification.

This invention relates to window regulators and has for its object an improved and 10 cheaper upper drum and spring retaining cup construction. In my copending application Serial No. 659,449, I have shown a drum which is preferably a die cast drum, 15 and a spring retaining cup which can be successfully used with this type of drum. It is the object of the present invention to provide a stamped metal drum which is also provided with a spring retaining cup which 20 has the dual function of housing the spring and also reinforcing the sheet metal drum.

In the drawings:

Fig. 1 is a side elevation of the upper portion of a regulator equipped with my improved drum and spring cup.

Fig. 2 is a section taken on the line 2—2 of Fig. 1.

Fig. 3 is a composite view showing the four operations which are performed on the 30 metal to form the drum.

Fig. 4 is an inside view of the drum and the cup showing the spring in place.

Fig. 5 is a cross section on the line 5—5 of Fig. 4, through the completed drum and 35 spring retaining cup.

Fig. 6 is a section taken on the line 6—6 of Fig. 2.

Fig. 7 is a section taken on the line 7—7 of Fig. 6.

The regulator is a cable type of regulator. 40 This is fully described and claimed in my copending application Serial No. 659,449, where the cable is shown running around the drum *a* a few times, and also wound 45 around the driving spool *b*. The cable is fastened to both the drum and the spool so that there is no possible slippage between the cable and the drum or spool. The 50 cable is as positive in this respect as the familiar chain type of regulator. *c* designates a direction-giving sheave for causing the cable to run alongside of the spacer bar *d* parallel therewith. *d'* designates a saddle for supporting the sash plate and 55 causing the same to ride on the flange *e*

of the drum so as to relieve the cable of the weight of the sash. This is described and claimed in my copending application Serial No. 672,793.

In order to meet the closely competitive 60 market that now exists in window regulators, and to afford a regulator which is within the reach of the low priced cars, it is imperative that the construction be just as cheap as possible and yet accomplish the 65 results sought. Counterbalancing springs have been considered somewhat of a luxury and not a necessity. In some of the cheaper types of regulators they have been eliminated to lessen the cost. However, they are 70 very desirable for good operation of the regulator because they equalize the driving effort required to raise the window and the driving effort required to push the window 75 down.

In my copending application Serial No. 659,449 I have shown and described a die cast cable drum. A die cast cable drum is a very good drum for the purpose, but die casting operations are relatively slow and 80 require the use of considerable metal. It is the object of the present drum and spring construction to substitute a stamping for the die cast drum. However, the problem is considerably more than simply specifying a 85 stamped drum in place of a die cast drum.

A piece of sheet metal is punched out as shown at *f* in Fig. 3. The second operation is to form or stamp it up into a cup *g*, as shown in Fig. 3. The third operation is to 90 reduce its diameter as shown at *h* to form a flange *e* at the base of the drum. The fourth operation is to roll the thread *j* on the drum. In order to permit this stamping, and especially the rolling of the thread, 95 it is necessary to use rather light stock. This stock is hardly strong enough to do the work assigned to it, hence I find it desirable to reinforce the drum. This I do without requiring an additional element by 100 simply telescoping the spring cup *k* in the drum so as to abut directly against the inside of the peripheral walls of the drum. It is desirable to have the spring cup as a separate article of manufacture so that the assembled spring may be shipped by the manufacturer of the spring to the regulator manufacturer. The spring maker either makes these spring cups or buys them and assembles the clock-like counterbalancing springs 105 110

m in the cup, and ships it to the manufacturer. Preferably, he places a paper washer *n* in the bottom of the cup so as to prevent the spring from drumming on the 5 metal cup when assembled in working relation.

The regulator manufacturer then assembles the parts together in this manner: The regulator plate is bossed out as at *o* (Fig. 10 2). This boss is adapted to seat the drum. At the center, four lugs *p* are struck out of the regulator plate to provide a guard to prevent the coiled spring from bearing on the drum hub. The regulator manufacturer 15 then takes a brass bushing or hub *r* which has a reduced end *q*. He places the spring cup telescopically within the drum, inserts the brass bushing or hub and then spins over the end of the hub, as shown at *s* in Fig. 5. 20 This locks the spring cup to the drum. One end of the counterbalancing spring is bent over and anchored in between the struck-out lug *t* of the spring cup and the rim of the cup, the other end of the spring is bent 25 over as at *u* and engages at the side of one of the guard lugs or posts at the center of the drum. Hence, one end of the spring is anchored to a stationary post and the other to a movable post. It will be seen that 30 when the spring cup is fitted into the drum this very materially reinforces the drum, which is made of relatively light gauge stock in order to permit the rolling of the thread. This construction makes a relatively cheap- 35 er drum construction than can be had by casting the drum.

What I claim is:

1. In a window regulator, a cable drum comprising a member formed of relatively thin sheet metal folded upon itself at one 40 side to form a flange, and having a continuous thread rolled in its periphery.

2. In a window regulator, a cable drum constructed of relatively light gauge material provided with thread rolled in its periphery, and a reinforcing cup or member secured within the drum to give the same a relatively greater rigidity than is permitted by the light gauge rolled drum periphery. 45

3. In a window regulator, a cable drum 50 constructed of comparatively light gauge sheet metal stock having a circumferentially corrugated periphery by reason of pressure applied thereto, and a reinforcing member closely telescoping within the drum and acting as a counterbalancing spring retainer. 55

4. In a window regulator, a sheet metal, circumferentially corrugated cable drum, a cup telescoping into the drum and acting as a reinforcement, and a hub member with a reduced end for riveting the reinforcing cup to the sheet metal drum. 60

5. In a window regulator, a regulator plate provided with a plurality of struck out guard posts, a sheet metal cable drum, a reinforcing cup secured in the drum and acting as a spring retainer, a hub for the drum, a bearing secured to the center of the regulator plate for rotatably mounting the hub of the drum within the guard posts, and a 70 coiled spring having its outer end secured to one of the guard posts which hold the same from constricting upon the hub. 75

6. In a window regulator, a cable drum of light sheet metal provided with an externally and internally corrugated periphery with corrugations running circumferentially, and a reinforcing cup telescoping closely in the cable drum for reinforcing the periphery thereof. 80

In testimony whereof he has affixed his signature.

ERNEST E. HEINTZ.
